COMPENSATING ROLL DRIVE MECHANISM

John L. Jones, North Billerica, Mass., assignor to Stockton Profile Gauge Corporation, Lowell, Mass., a corporation of Massachusetts

Original application May 5, 1937, Serial No. 140,998, now Patent No. 2,220,737, dated November 5, 1940. Divided and this application September 13, 1940, Serial No. 356,591

10 Claims. (Cl. 271—2.6)

This invention relates to compensating roll drive mechanisms, and with regard to certain more specific features, to such mechanisms for use with web alignment detectors.

The invention is a division of the invention described in the application of John L. Jones, Serial No. 140,998, filed May 5, 1937, for Apparatus for detecting web alignment, eventuated into Patent No. 2,220,737, dated November 5, 1940.

Among the several objects of the invention may be noted the provision of a compensating roll drive mechanism adapted under automatic control to correct in a relatively simple and effective manner both lateral and longitudinal misalignments in moving webs; the provision of a mechanism of the class described which applies corrections in a resilient manner to avoid subjecting the web being corrected to tension of web-breaking magnitude; the provision of apparatus of the class described in which the resilience is determined by the tear strength of the web; and the provision of apparatus of this class which is energized from rotary driving means or the like. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a diagrammatic side elevation of a press, showing a drive mechanism for a compensating roll;

Fig. 2 is a front elevation of a ratchet drive shown in Fig. 1;

Fig. 3 is an enlarged front elevation of a pawl shown in Fig. 2;

Fig. 4 is a side elevation of the ratchet drive shown in Fig. 2;

Fig. 5 is an enlarged front elevation of connecting means on the end of a press roll, as found in Fig. 1;

Fig. 6 is an enlarged bottom plan view of the connection shown in Fig. 5;

Fig. 7 is an enlarged cross section showing the manner in which a drive rod is pivoted in connection with the mechanism of Figures 5 and 6;

Fig. 8 is a top plan view of a compensating roll;

Fig. 9 is a cross section taken substantially

along line 9—9 of Fig. 8, showing an outside elevation of a dual control arm;

Fig. 10 is a cross section similar to Fig. 9, but showing an alternative position of the control arm;

Fig. 11 is a cross section taken substantially along line 11—11 of Fig. 8, showing the inside elevation of said dual control arm;

Fig. 12 is a cross section taken substantially along line 12—12 of Fig. 8, showing the outside elevation of a simple control arm;

Fig. 13 is a cross section taken substantially along line 13—13 of Fig. 8, showing the inside elevation of said simple control arm;

Fig. 14 is a cross section taken on line 14—14 of Fig. 9, showing a pivot pin and drive nut; and,

Fig. 15 is a fragmentary rear elevation of the compensating roll of Fig. 8.

Similar reference characters indicate corresponding parts throughout the several views of the drawings.

The present invention is adapted for use with alignment detectors, both lateral and longitudinal, of the stroboscopic type, in connection with the disclosure made in said Patent No. 2,220,737 wherein details of the detectors may be found. The mechanism herein described operates on the selective reception of electrical impulses from one or the other of two sources, in a manner stated in said application.

Referring now more particularly to Fig. 1, numeral 310 indicates a stationary bracket or similar member that is securely fastened to a press frame. Numeral 311 indicates the main shaft of the press cylinder 11, which is arranged to extend through the bracket 310. To the end of shaft 311 is made fast a gear 312. Numerals 313 and 314 indicate gears that mesh with the gear 312, and which are individually freely rotatable on studs 315 and 316 (see also Fig. 6) mounted in the bracket 310. The gears 313 and 314 are of special construction, having diametrical slots 317 extending across the faces thereof.

As indicated more particularly in Fig. 7, the slots 317 have a T cross section, with the cross bar of the T downward. This shape of slots 317 provides for the accommodation of a bolt 318, the head 219 of which fits the cross portion of the slot 317 and is there securely held. The shank of the bolt 318 receives a collar or bearing member 319, which is held in position by a nut 320. Surrounding the bearing member 319 is the suitably recessed end of a link or connecting rod 321, for the gear 313, and an analogous

link 322 is used for the gear 314. By loosening the nuts 320, the relative position of the ends of links 321 and 322 at the respective slots 317 of gears 313 and 314 may be adjusted for purposes hereinafter to be described.

Referring again to Fig. 1, and also to Figures 2 and 4, numeral 323 indicates a jack shaft that is supported at its end in suitable bearings (not shown). At one end, the shaft 323 carries a helical gear 324, which engages a helical gear 325 which may be located, for example, on an extension of the shaft 228 arranged for the drive of the longitudinal corrective means on the compensating roll of the type described in said patent application. The gear 324 is made fast to the shaft 323.

Numerals 326 indicates a ratchet wheel that normally turns loosely on the shaft 323. Numeral 327 indicates a similar, but oppositely facing ratchet wheel that likewise turns freely on the shaft 323. Frictionally engaging the respective outer faces of ratchet wheels 326 and 327 are discs 326A and 327A, which are likewise rotatable on shaft 323. Friction disc 326A is held firmly against ratchet wheel 326 by a compression spring 328, the other end of which reacts against the inner face of worm wheel 324, while friction disc 327A is similarly held firmly against ratchet wheel 327 by a compression spring 329, the other end of which reacts against a disc 330 made fast on shaft 323. The compression spring 328 is secured at its ends to disc 326A and worm wheel 324, and compression spring 329 is secured at its ends to disc 327A and disc 330. The springs 328 and 329 hold the respective discs 326A and 327A against their ratchet wheels 326 and 327 so that frictional drive relationships are had between ratchet wheel 326 and shaft 323, on the one hand, and ratchet wheel 327 and shaft 323, on the other hand, but discs 326A and 327A will slip on their respective ratchet wheels before they transmit a drive that would tend to jam the shaft 323. These friction discs 326A and 327A may accordingly be designated as anti-jamming or overload devices.

Numerals 331 indicates a radial arm that is loosely swingable on the shaft 323, and is positioned between the ratchet wheels 326 and 327 but close to the ratchet wheel 326. An analogous arm 332 is positioned next to the ratchet wheel 327. To the end of arm 331 is pivoted, as by a pin 333, the other end of link 321, while a similar pin 334 holds the other end of link 322 to the outer end of arm 332. On the arm 331 is mounted an electromagnet or solenoid indicated by numeral 335, and a freely swinging armature 336 is articulated to the movable core 331 of the solenoid 335. The armature 336 is preferably suspended on a light leaf spring 338, in the manner indicated. The lower end of armature 336 is connected to a portion indicated by numeral 339, and the extreme end of portion 339 is pivoted, as by a pin 340, to a short link 341. The other end of link 341 rotates about a pivot pin 342 mounted in the arm 331. Also rotatably mounted on the pin 342 (see also Fig. 3) is a pawl 343, which has a rearward up-turned portion 344 adapted to engage the side of link 341. A compression spring 345 operating between an ear 346 on the pawl 343 and an ear 347 on the link 341, tends at all times to force the pawl 343 to rotate in a counter-clockwise direction, as illustrated in Fig. 3. The lower end 348 of pawl 343 is shaped to engage the teeth of ratchet wheel 326.

The compression spring 345 normally holds the pawl 343 in such a manner that the projection 344 abuts the side of link 341. The spring 338 normally holds the armature 336 away from the electromagnet 335, or, in other words, with the core 331 in its extended position. This positioning of the armature 336 through the action of the portion 339 on link 341, normally rotates the whole pawl assembly so that it is free of any engagement with the teeth of ratchet wheel 326.

The arm 332 is provided with a similar assembly of elements, including an electromagnet 349, an armature 350, an armature supporting spring 351, and a pawl 352. These elements numbered 349 through 352, inclusive, all have analogous functions to their similar elements mounted on arm 331, but face in an opposite direction and engage the ratchet wheel 327.

Electrical connection is made from one of the thyratron sources of said Fig. 13 of said patent application, for example, to the electromagnet 335, and from the other thyratron of said circuit of said patent application to the electromagnet 349.

The operation of the drive mechanism as thus described is as follows:

The constantly rotating gear 312 constantly rotates the gears 313 and 314. Links 321 and 322 now function as connecting rods, and serve to oscillate their respective arms 331 and 332 on the shaft 323. The oscillations of the arms 331 and 332 may be regulated to any desired amount by loosening the nuts 320 and adjusting the position of bolts 318 in slots 317, as will be obvious from the drawings.

As long as no power reaches either of the electromagnets 335 or 349 from the circuit, both pawls 343 and 352 are held out of engagement with their respective ratchet wheels 326 and 327. The arms 331 and 332 thus reciprocate idly on the shaft 323.

If, now, power is supplied to either the electromagnet 335 or to the electromagnet 349, the respective electromagnet, for example 335, is energized; and in the case of said electromagnet 335, it draws in its core 331, moving the armature 336 to the left in Fig. 2. Portion 339 of armature 336 then rotates link 341 to the left, and thus throws the lower end 348 of pawl 343 into engagement with the teeth of ratchet wheel 326. Whenever, now, the arm 331 enters a counter-clockwise phase of its oscillation, the end 348 of pawl 343 moves against a tooth of ratchet wheel 326 and drives said ratchet wheel in a counter-clockwise manner. The clockwise reciprocation of arm 331 is, however, ineffective to rotate the ratchet wheel 326, because, for a relative clockwise rotation of the arm 331, the compression spring 345 permits the pawl 343 to spring aside over successive teeth of the ratchet wheel 326.

By a similar, but reverse movement, whenever the electromagnet 349 on arm 332 is energized, the ratchet wheel 327 will be rotated, intermittently, in a clockwise direction, but left free under the back-springing action of the pawl 352, under counter-clockwise reciprocations of the arms 332.

The clockwise rotation of the ratchet wheel 327, or the counter-clockwise rotation of the ratchet wheel 326, as thus brought about, is transmitted to the shaft 323 by friction discs 327A or 326A, and spring 329 or 328, respectively, acting on disc 330 or worm wheel 324. The purpose for including the springs 328 and 329 in

the drive is to prevent too abrupt a movement or rotation of the shaft 323. This prevents too abrupt a movement of the shaft 228. It is clear that rotation of the shaft 323 through interaction of the worm wheel 324 and worm 325 drives the shaft 228 to a selective rotation, and shaft 228 in turn selectively drives the worm 227 which reacts upon sector gear 225 of the frame holding the compensating roller 188.

Returning to Fig. 1, it will be seen that another shaft 353 similar in all respects to the shaft 323 is provided, and that this shaft 353 carries an assembly of ratchet wheels, reciprocating arms, and the like, all of which are analogous to the similar elements provided on shaft 323. In order to drive the reciprocating arms of the assembly on shaft 353, connecting links 354 and 355 are provided to the ends of the respective arms 331 and 332 of the assembly on shaft 323.

It will be understood from said patent application that the electromagnets of the assembly on shaft 353 are electrically connected to a lateral alignment detector, whereas the electromagnets of the assembly on shaft 323 are electrically connected to a longitudinal alignment detector.

Shaft 353 drives a shaft 357 through a helical gear 356. The shaft 357 is connected through a flexible drive shaft 214 to a lead screw 212 operating in a nut 215 associated with the compensator roll 188.

Referring again to Fig. 1, it will be noted that a similar driving means is provided on the cylinder 12 of the press. This driving means is made selectively to operate the lateral and longitudinal correcting portions of another compensating roll (not shown). Similar drive mechanism may be provided for any or all of the compensating rolls in a press system.

The compensator roll 188 operates upon a web 40 W which passes between rollers 11 and 12 and compensation is effected by the mechanism shown in Figs. 8-15 herein.

The compensating roll is shown in Figs. 8-15, to which attention is now directed. Referring to these figures, and more particularly to Fig. 8, numeral 188 indicates the roller just mentioned. The roller 188 is mounted upon a shaft 189, the ends of which are received in suitable anti-friction bearings 190 and 191 mounted in arms 192 and 193, respectively. The arm 192 is simplest in construction, and will first be described. It comprises a simple radial arm extending from a hub 194 which is secured by set screws 195 to a shaft 196 which extends the width of the press. The roller 188, it will be understood, is preferably slightly longer than the width of the web. One end of the shaft 196 is rotatably received in a bearing 197, while the other end is likewise rotatably received in a bearing 198. Shaft 196 has a portion 199 of reduced diameter at the end which enters the bearing 198.

Both extreme ends of the shaft 196 are preferably provided with collars 200 through which extend taper pins 201 for holding the shaft 196 against sidewise motion in the bearings 197 and 198.

The arm 193 comprises a collar 202, which is secured to the shaft 196 by set screws 203. From the collar 202 extends a bracket or arm 204, in which is received a stud 205 provided with a bearing surface 206. A screw 207 secures the stud 205 against rotation in the arm 204. The axis of the stud 205 is parallel to the axis of the shaft 196. Rotatably mounted on the bearing 75

portions 206 of stud 205 is a collar 208, from which extends a radial arm 209. The roller bearing 191 is mounted at the far end of arm 209.

Referring now to Fig. 9, it will be seen that the bracket or arm 204 has at its extreme end a pair of parallel projections 210. On the outer faces of the two projections 210 are mounted roller or like frictionless bearing elements 211, and these bearings 211 serve to mount therebetween a lead screw 212, which extends through the projections 210 and across the space therebetween. At its lower end, the lead screw 212 is connected by a suitable coupling 213 to a flexible shaft 214. Threaded on the lead screw 212 is a nut 215 which has a cylindrical portion 216 extending inwardly, its axis being parallel to the axis of the stud 205. Portion 216 receives a roller 217, and the roller 217 is held in position on the portion 216 by a washer 218 and a screw 219, as indicated in Fig. 14. The roller 217 slides up and down in a slot 220 provided therefor in arm 209.

It will now be seen that if the lead screw 212 is rotated, the nut 215 will move up and down said lead screw, relative to the bracket or arm 204, and that motion of the nut 215 in the manner described will in turn cause rotation of the arm 209 pivoting on stud 205. By way of illustration, Figures 9 and 11 show the relative position of the arms 204 and 209 when the nut 215 is at the bottom of the lead screw 212, while Fig. 10 shows the relative position of the arms 204 and 209 when the nut 215 is at the top of the lead screw 212. The relative motion of the roller 188 thus brought about by turning the lead screw 212 is a tilting motion, and results in an adjustment of the angle made by the axis of roll 188 with the axis of shaft 196. When the nut 215 is in its central position on lead screw 212, the arms 204 and 209 are so positioned, relative to each other, that the axis of the roller 188 is parallel to the axis of shaft 196.

The bearings 190 and 191 for the ends of shaft 189 of roller 188 are purposely made in such a manner as to permit the tilting of the roller 188 in the manner described; such as self-aligning ball bearings.

Returning again to Fig. 8, it will be seen that the collar 202, and brackets 204, are provided with a forwardly extending flange or collar 221. Additional set screws 222 are desirably provided in the collar 221, for securing the assembly firmly to the shaft 196. The face of collar 221 receives one end of a tension or coil spring 223 that is wrapped around the shaft 196. The other end of the coil spring 223 is firmly mounted in the face of a collar 224 which rotates upon the portion of reduced diameter 199 of the shaft 196. The collar 224 is secured against longitudinal movement relative to the shaft 196 by positioning it between the bearing 198 and the shoulder resulting from the portion of reduced diameter 199. Extending downwardly from the collar 224 is a sector-shaped gear 225, the lower periphery of which is toothed, as indicated at numeral 226 in Fig. 15, to engage the threads of a worm wheel 227. The worm wheel 227 is in turn mounted on a shaft 228.

Numerals 229 indicates an arcuate slot that is provided in the collar 224, and numeral 230 indicates a radial pin that is mounted in the shaft 196 in position to engage the ends of slot 229. Normally, the pin 230 is positioned to abut the end of slot 229.

The operation of the compensating roll as thus described is as follows:

The roller 188 frictionally engages the moving web. The bearings 197 and 198 are so positioned that the shaft 196 is supported with the roller 188 in the desired engagement with the web. It will be assumed, for the moment, that the nut 215 is located midway on the screw 212.

Assume now that the longitudinal detector calls for a correction in a direction requiring take-up, or tightening of the web W. This means that the shaft of the ratchet motor arrangement will be rotated in a direction tending to rotate the worm wheel 227 in a clockwise (Fig. 15) direction, thus rotating the sector gear 225 also in a clockwise direction. The sector gear will accordingly be rotated as long as longitudinal correction is required. Rotation of the sector gear is transmitted, through the spring 223, to the collar 221, and consequently the shaft 196 is resiliently driven to rotate. The action of the spring 223 is to introduce resilience into the rotation of the shaft 196, so that it will not too suddenly rotate and possibly thereby break the moving web of paper. Ultimately, the spring 223 will rotate the shaft 196 sufficiently far so that pin 230 is brought to abut the end of slot 229. In rotating, the shaft 196 carries with it the arm 192 and the now relatively rigid assembly comprising arms 204 and 209, and thus shifts the roller 188 downwardly with its axis remaining parallel to the axis of shaft 196, to take up web material and hence to retard, relatively, the progress of the web and thus achieve a desired longitudinal correction.

If the longitudinal detector calls for a correction in the opposite direction, namely, requiring a loosening, or relative advancement, of the web, then the shaft of the ratchet motor arrangement will be rotated in a direction tending to rotate worm wheel 227 in a counter-clockwise (Fig. 15) direction, thus rotating the sector gear 225 also in a counter-clockwise direction. Rotation of the sector gear 225 is now directly transmitted to shaft 196 by the abutment of pin 230 on the end of arcuate slot 229 (the normal position of pin 229). Resilient drive of the shaft 196 is not now needed, because the corresponding upward shifting of roller 188 tends to relax tension on the web W, rather than to increase such tension, and hence there is present no tendency to break the web W. The upward movement of roller 188 loosens the moving web W and hence relatively advances it in its longitudinal travel.

Lateral adjustment is accomplished through rotation of the lead screw 212, as above described, causing the nut 215 to move up and down with relative rotation of the arm 209 on bracket 204. The net result of this movement is to tip or tilt the axis of rotation of the roller 188. By tilting the roller 188, the direction in which the web is proceeding is altered, and by altering this direction, the lateral misalignment is corrected. If the direction of lateral misalignment is against the travel of the web, the extra pressure on the web resulting from the correcting tilting of the roller 188 is temporarily transferred to spring 223, by the reaction through pin 230 in its normal position of rest against the end of arcuate slot 229. In a brief time, however, spring 223 returns to its present position, thus applying the full lateral correction required in a resilient manner. The correction of a lateral misalignment with the direction of travel of the web relieves normal

web tension, and hence no resilient application of the correction is needed.

After a lateral correction the roller 188 usually remains in a tilted position, and when a longitudinal correction is then needed, it is applied in the same manner already described, the effect of the applied longitudinal correction still being to shift the roller 188 as a whole, keeping its axis of rotation parallel. Obviously, therefore, a longitudinal correction may be accomplished without introducing, thereby, a lateral misalignment, and vice versa.

It will accordingly be seen that a compensating roll of great compactness and efficient operation is provided, for operation in conjunction with the misalignment detectors, both lateral and longitudinal, heretofore described.

It will be noted that in effect the gear 312 is synchronized with the cylinder 11 and that the same compensating effects could be obtained by driving the ratchet mechanism from a similar gear which, instead of being driven by the cylinder 11, could be driven by a separate motor synchronized with the cylinder 11. This is mentioned to indicate what would be considered to be one of the possible mechanical equivalents which might be used.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A compensator for a moving web which passes over rotary cylinders comprising a roller 40 on the web for displacing the web, a swinging frame supporting the roller, drive means for biasing the roller in the frame, drive means for swinging the frame, separate ratchet means in each of said drive means, a pair of pawls associated with the respective ratchet means adapted selectively to drive the ratchet means in one or the other direction, oscillating means for the ratchets operating the respective ratchets of each pair in opposite directions, means for driving the oscillating means synchronously with said cylinders, means for normally retracting said pawls from their ratchets, and means for selectively forcing the pawls toward engagement.

2. A compensator for a moving web comprising a roller on the web for displacing the web; a swinging frame supporting the roller; drive means for biasing one end of the roller in the frame, drive means for swinging the frame, separate ratchet means in each of said drive means, a pair of pawls associated with the respective ratchet means adapted selectively to drive the ratchet means in one or the other direction, oscillating means for the ratchets, means for driving the oscillating means, said pawls normally being retracted from their ratchets, and means for selectively individually forcing the pawls toward engagement.

3. Adjusting means for elevation and tilt of a roller comprising separate ratchet means respectively for elevation and tilt, a pair of pawls for each ratchet means, separate oscillating means for the respective ratchet means of each pair, means for driving said separate oscillating means which are oppositely phased to provide opposite movement, corresponding members of both pairs

of ratchet means being mechanically connected to a given driving means for similarly phased movement, means normally biasing the pawls away from their ratchet means, and means for selectively moving them against the respective ratchet means.

4. A compensator for a moving web which passes over a rotary cylinder, comprising a roller on the web for displacing the web, a swinging frame supporting the roller, a first drive means for swinging the frame, a second drive means for biasing the roller in the frame, a reversible ratchet means in each driving means, a pair of independently swinging arms associated with each ratchet, eccentric means driven by the rotary cylinder, connecting rods respectively connected between the eccentric means and each of a pair of said radial arms which are associated with one of the eccentrics, the eccentrics being angularly phased with respect to one another, whereby said radial arms move in opposite phases, means respectively linking members of one pair of radial arms with the members of the other pair of radial arms in equal phase relationships, a pawl mechanism on each arm, the pawl mechanisms on oppositely phased arms being arranged for driving the respective ratchet means in opposite directions, and means on the respective arms for controlling the respective ratchet means thereon for connection and disconnection from the ratchet means, the controlling means on oppositely phased arms being independent.

5. A compensator for a moving web which passes over a rotary cylinder, comprising a roller on the web for displacing the web, a swinging frame supporting the roller, a first drive means for swinging the frame, a second drive means for biasing the roller in the frame, a reversible ratchet means in each driving means, a pair of independently swinging arms associated with each ratchet, two independently adjustable eccentric means geared to the rotary cylinder, connecting rods respectively connected between the eccentric means and each of a pair of said radial arms which are associated with one of the eccentrics, the eccentrics being angularly phased with respect to one another, whereby said radial arms are oppositely phased, means respectively linking members of one pair of radial arms with the members of the other pair of radial arms in equal phase relationships, a pawl mechanism on each arm, the pawl mechanisms on oppositely phased arms being arranged for driving the respective ratchet means in opposite directions, and means on the respective arms for controlling the respective ratchet means thereon for connection and disconnection from the ratchet means, the controlling means on oppositely phased arms being independent.

6. A compensator for a moving web which passes over a rotary cylinder, comprising a roller on the web for displacing the web, a swinging frame supporting the roller, drive means biasing the roller in the frame, separate driving means for respectively swinging the frame and biasing the roller in the frame, separate ratchet means in the respective drives, levers adjacent the respective ratchet means in the respective drives equally phased and of equal length, said levers being connected by a connecting rod, a pair of oppositely phased levers respectively adjacent said ratchet means also of equal length and between themselves being equally phased, said last-named levers also being connected by means of a connecting rod, and separate eccentric means

connected with the oppositely phased pairs of levers, means for driving said eccentric means from the rotary cylinder, forward and reverse pawls on the respective levers selectively engageable with the ratchet means for forward or reverse movement of said ratchet means, each pawl being operable independently of the other.

7. In a web compensator, a ratchet wheel, an oscillating lever adjacent to the wheel, an electromagnetic coil supported on the lever for movement therewith, an armature having relative movement with respect to said coil and operative thereby, means for mounting said armature on the lever comprising a spring fixed to the lever on the one hand and to a movable member supporting the armature on the other hand, a pawl pivoted to the oscillating lever, and means connecting said armature-supporting member and the pawl for operating the latter.

8. In a web compensator, a ratchet wheel, an oscillating lever adjacent to the wheel, an electromagnetic coil supported on the lever for movement therewith, an armature having relative movement with respect to said coil and operative thereby, means for mounting said armature on the lever comprising a spring fixed to the lever on the one hand and to a movable member supporting the armature on the other hand, a pawl pivoted to the oscillating lever, and means connecting said armature-supporting member and the pawl for operating the latter, said last-named means comprising a link pivoted adjacent to the pawl, spring means reacting between the link and the pawl normally biasing the latter toward the ratchet wheel in one position of the link, a dog on the ratchet engageable by said link for retraction of the pawl from the ratchet in another position of said link, and a connecting rod between the link and said armature-supporting member.

9. A compensator for a moving web which passes over rotary cylinders, comprising a roller on the web for displacing the web, a swinging frame supporting the roller, a bearing at one end of the roller and the frame permitting tilting of the roller, a bearing at the other end of the roller, a swinging arm pivoted to the frame and supporting said other bearing, a mechanism carried on the frame and cooperating with the arm to adjust the arm whereby the roller is tilted from its end carried in the arm, a shaft, said frame oscillating around the center line of the shaft, rotary means for oscillating the frame, and resilient means connecting said rotary means and the frame.

10. A compensator for a moving web which passes over rotary cylinders, comprising a roller on the web for displacing the web, a swinging frame supporting the roller, a bearing at one end of the roller and the frame permitting tilting of the roller, a bearing at the other end of the roller, a swinging arm pivoted to the frame and supporting said other bearing, a mechanism carried on the frame and cooperating with the arm to adjust the arm whereby the roller is tilted from its end carried in the arm, a shaft, said frame oscillating around the center line of the shaft, rotary means for oscillating the frame, resilient means connecting said rotary means and the frame, and a flexible driving means for transmitting motion to the arm-adjusting means in any position of the frame around the center line of said supporting shaft.
